UNITED STATES PATENT OFFICE

2,248,597

AUTOMATIC CONTAINER WASHING
MACHINERYRobert J. Wynne, Bellwood, Ill., assignor to
Irving D. Porter

Application April 20, 1936, Serial No. 75,361

36 Claims. (Cl. 15—61)

This invention relates to automatic container washing machinery, and more particularly to such a machine for washing bottles, cans, and kindred types of receptacles. The general object of my invention is to provide a machine for washing bottles by brushing both inside and outside simultaneously while the bottles are submerged in an appropriate solution for removing all solid foreign matter, including old labels, prior to the transfer to a sterilizing bath or treatment.

A specific object is to provide mechanism to accomplish the foregoing object, in which all the steps of feeding the bottles into and out of said solution, the washing and the transfer to the sterilizer are completely automatic.

A further specific object is to provide automatic mechanism for simultaneously washing a number of bottles both inside and outside by rotation while submerged in a solution and for automatically transferring said bottles into and out of said solution.

Other incidental and related objects and advantages will become obvious and be particularly pointed out in the following description, reference being had to the accompanying drawings, in which:

Fig. 1 is a side elevational view of the exterior of my bottle washing machine, showing a portion of the sterilizing machine in conjunction with which it is adapted to operate;

Fig. 2 is a similar view, showing the remainder of the sterilizing machine of Fig. 1;

Fig. 3 is a plan view taken on the line 3—3 of Fig. 1, showing the reciprocating power drive rod;

Fig. 4 is a cross-sectional view taken on the line 4—4 of Fig. 3, showing the clamping pivot of the conveyor drive and reciprocating power drive;

Figs. 5 and 5A, taken together, are an enlarged plan view, partly broken away, taken on the line 5—5A of Fig. 1, Fig. 5 showing the feeding mechanism, pivoted feeding table, and dumping elevator, and Fig. 5A showing the discharge tracks from the dumping elevator and discharging of bottles into the sterilizing mechanism;

Figs. 6 and 6A, taken together, are an enlarged plan view taken on the line 6—6A of Fig. 1, Fig. 6 showing the spindle drive, the idle and pick-up power carriage, and push and pull rod of the reciprocating power carriage, and Fig. 6A showing the reciprocating power carriage advanced to the conveyor bottle carriers to discharge bottles for washing, and the mechanism for driving the conveyor;

Fig. 7 is an enlarged end view taken on the

line 7—7 of Fig. 1, partly broken away, showing the beginning of the feeding of the bottles to the pivoted swinging table and the drive for the rotary spindles;

5 Figs. 8 and 8A, taken together, are a side sectional elevation taken on the lines 8—8 and 8A—8A, respectively, of Figs. 5 and 5A, Fig. 8 showing the feeding advance of the bottles to the pivoted swinging table, the discharge of the bottles upon the dumping elevator, the spindle drive with the bottles being washed, the idle pick-up power carriage in position for forward movement, and the conveyor in a stationary position; and Fig. 8A showing the reciprocating power carriage, the discharge of the bottles from the conveyor, the discharging of the bottles from the dump elevator to the sterilizing machine, and the conveyor driving mechanism;

10 Fig. 9 is an enlarged end elevation taken on the line 9—9 of Fig. 1, showing the drive for the conveyor, and the discharge mechanism of the bottles to the sterilizing machine;

15 Fig. 10 is a cross-sectional view taken on the line 10—10 of Fig. 8, showing the feeding and discharge end of the conveyor, resilient bottle stop strips and guide to discharge track, conveyor guides, and centering mechanism with back dash stop and reciprocating power carriage;

20 Fig. 11 is a cross-sectional view taken on the line 11—11 of Fig. 8A, showing the reciprocating power carriage, also the mechanism for discharging bottles from the conveyor and discharging carriage for discharging the bottles to the sterilizing machine, with centering mechanism and back dash stop;

25 Fig. 12 is an enlarged fractional view of a portion of Fig. 8, emphasizing the swinging table, the dumping elevator having just received a bottle from the conveyor, the rotary spindle drive with bottles out of the conveyor and being washed inside and outside, and the beginning of a forward movement of the power carriage;

30 Fig. 13 is a longitudinal view similar to Fig. 12, showing the idle pick-up power carriage advanced somewhat, the swinging table advancing the bottle from the inclined position shown in Fig. 12, the dumping elevator in intermediate position, and a washed bottle being returned to the conveyor;

35 Fig. 13A is a detail sectional view of the dumping elevator in a horizontal position and pick-up and kick-back frame in a closed position;

40 Fig. 14 is a longitudinal view similar to Fig. 13, showing the complete forward movement of the

idle pick-up power carriage and parts operated therefrom;

Fig. 14A is a detail elevational view of one end of the idle pick-up power carriage and the release mechanism;

Fig. 15 is a cross-sectional view taken on the line 15—15 of Fig. 13, showing the idle pick-up power carriage, the feeding advance carriage, and the pivoted swinging table and dumping elevator in idle position;

Fig. 16 is an enlarged view of the portion shown in Fig. 8 of the feeding advance carriage, partly broken away, and in section to show the relation thereof to the pivoted swinging table;

Fig. 17 is a fragmentary view showing the principal operating parts for the feeding advance mechanism, and showing also the primary operating arm for the pivoted swinging table;

Fig. 18 is a fragmentary sectional view taken along the line 18—18 of Fig. 17, and illustrating the feeding fingers for the feeding advance mechanism;

Fig. 19 is a partial sectional elevation taken along the line 19—19 of Fig. 13, showing details of the dumping elevator mechanism, the pivoted swinging table in horizontal position, the outside brushing mechanism, and the releasing mechanism of the idling pick-up power carriage;

Fig. 20 is a fragmentary sectional view taken along the line 20—20 of Fig. 19, showing the mounting of the elevating member;

Fig. 21 is an enlarged partial sectional view taken along the line 21—21 of Fig. 22, illustrating the conveyor centering mechanism shown also on Figs. 10 and 11 and including in section parts of the adjacent conveyor;

Fig. 22 is a plan section of the subject matter of Fig. 21 taken along the line 22—22 of Fig. 21, but showing the centering mechanism in raised position;

Fig. 23 is a fragmentary view in central sectional elevation of the back dash stop, which may also be seen in Figs. 10 and 11;

Fig. 24 is a plan section taken along the line 24—24 of Fig. 14, showing the mechanism in a slightly advanced position and illustrating the kick-back lever mechanism for releasing the spindles from the bottles;

Fig. 25 is a partial sectional elevation taken on the line 25—25 of Fig. 24;

Fig. 26 is a fragmentary sectional elevation taken along the line 26—26 of Fig. 24, showing the cam roller connection with one of the spindles;

Fig. 27 is a fragmentary view showing the eccentric mounted roller shown in Fig. 24;

Fig. 28 is a partial sectional elevation taken on the line 28—28 of Fig. 6A, illustrating the conveyor centering mechanism;

Fig. 29 is a fragmentary sectional elevation taken along the line 29—29 of Fig. 5A, showing the friction latch which actuates in conjunction with the sterilizing feeding mechanism;

Fig. 29A is a fragmentary elevational view showing in enlarged detail a portion of the sterilizer feeding mechanism;

Fig. 30 is an enlarged detail showing two of the elevating members;

Fig. 31 is a sectional elevation through one of the conveyor carriers shown partially in Figs. 8 and 8A;

Fig. 32 is a partial elevation substantially similar to Fig. 31, showing a half pint bottle just having been inserted into a carrier and showing the actuating mechanism just prior to being dis-

connected from the conveyor carriage plungers;

Fig. 33 is an enlarged fragmentary view illustrating one of the spring clips shown in Fig. 8A in engagement with one of the ejector rods;

Fig. 34 is an elevation in central section of one of the rotating spindles in retracted position;

Fig. 35 is a cross-sectional view taken on the line 35—35 of Fig. 34;

Fig. 36 is an enlarged sectional elevation of one of the carriers in the lowermost position of the conveyor, showing a portion of the cooperating spindle mechanism and showing a bottle partially removed from the carrier during the washing operation;

Fig. 37 is a plan section of the mechanism shown in Fig. 36, omitting the spindle;

Fig. 38 is a detail face view of one of the brush holder rocker arms and connected brush;

Fig. 39 is a side view of the same;

Fig. 40 is a view similar to Fig. 36, showing a pint bottle completely inserted in a carrier;

Fig. 41 is a view taken substantially along the line 41—41 of Fig. 36, partially broken away, showing the brush holder cam arms in the position shown in Fig. 40;

Fig. 42 is a plan section of the mechanism shown in Fig. 32;

Figs. 43 and 44 are face and side view, respectively, of one of the brush holders and brush;

Fig. 45 is a detail view of one of the brush holder clip bars;

Fig. 46 is a face view of one of the bristle clamps;

Fig. 47 is a section taken on the line 47—47 of Fig. 46; and

Fig. 48 is a section taken on the line 48—48 of Fig. 46, including the clip bar of Fig. 45.

In the bottle or container washing industry or art two important steps or functions are involved, 40 and these are: first, the washing or cleansing in the ordinary sense of these terms; and second, the sterilizing stage. It has been customary heretofore to accomplish these two results in a single machine, an important disadvantage of which is 45 that no means are provided for detecting or throwing out any bottles which because of excessive or adhering dirt matter have not been thoroughly washed before being passed to the sterilizing stage. Furthermore, it has been customary to sterilize the containers before the washing or brushing operation has been completed. These problems were recognized and to a degree solved by me as disclosed in previous patents, Nos. 1,988, 963, 1,981,684, and 2,044,041. In my 55 present invention I reverse the usual procedure in some systems and machines and brush or scrape the containers before sterilizing them.

Further improvements are embodied in my present invention wherein two separate though correlated and synchronized units are provided for the washing and sterilizing processes, the action being entirely automatic including the transfer of the bottles from the washing unit to the sterilizing unit. However, an opportunity is afforded for an inspection of the bottles after washing and before the sterilizing in order that any that have escaped a thorough washing may be removed and will not be passed through the sterilizing unit until after re-washed or specially cleaned. A synchronized mechanism is provided, wherein the bottles are fed into a conveyor in the washer, the conveyor passing them into a washing solution. The bottles are then removed from the conveyor for a brushing stage, and returned to the conveyor for discharge onto a feeding

mechanism for feeding them into the sterilizing unit.

For convenience and in order to permit a ready understanding of my invention I have designated the various operating sub-units by group numeration. For example, the mechanism generally involved in the initial feeding and advancing of the bottles into the washing unit is designated by A with the detailed parts therein given numbers all preceded by the letter A. A pivoted feeding table to which the bottles from A are advanced is likewise designated B. From this table the bottles are passed into a conveyor C and conveyed to the region where a plurality of rotary spindles D engage them for the washing step. The conveyor then carries them to the upper part of the machine where they are discharged onto an elevator E and transferred to the sterilizing unit F. The foregoing devices are all actuated by a single power drive consisting principally of a reciprocating power frame G, which in turn actuates an idling pick up power carriage H for certain steps of the unitary operation.

Referring more particularly to the drawings and especially to Figs. 1-4, inclusive, the sterilizing machine comprises a main housing 20 which encases most of the mechanism and has therein a soaking tank 21, cleansing spraying means 22, and conveyor chains 23 having rollers 24 traveling on guides or trackways 25. Chains 23 travel over sprockets 26 which are supported by shafts 27. A pair of longitudinally movable and adjustable sprockets 28 are supported by shafts 29. The shaft 29 is supported by a pair of adjusting plates 30 having slots 31 which are slidably mounted on studs 32 supported by the side walls of housing 20. A channel iron of the framework 33 has its laterally extending flanges apertured and threaded to receive an adjusting screw 34 for the purpose of moving the plate 30. By means of plate 30 and adjusting screw 34 it can be seen that the shaft 29 may be moved longitudinally of the machine in order to take up slack or relieve the tension on conveyor chain 23.

A pair of horizontal and longitudinally extending angle irons of frame work 33 support a motor 35 and gear reduction box 36. Gear reduction box 36 has a power shaft 37 extending laterally therefrom, and sprockets 38 are keyed to shaft 37 and receive chains 39 which mesh with sprockets 40 which are keyed to main transverse takeoff shaft 41 whose ends are received in bearings 42 secured to the side walls of housing 20. A crank 43 is keyed to each end of shaft 41, and transmits power to connecting rods 44 which are in turn connected to legs 45 of bell cranks 46. Bell cranks 46 are supported by a transversely extending shaft 47 whose ends are received in bearings 48 anchored on the side walls of housing 20. Inferiorly of casing 20 a pair of arms 49 are keyed to shaft 47 and transmit power to a pair of adjustable conveyor advancing members 50 and 51 which have hook-like chain engaging ends 52 for cooperation with the cross members of conveyor chains 23. The upper extremities of members 50 and 51 are provided with arcuate cam surfaces 53 which ride on deflecting angle iron guide plates 54, and are thus raised vertically by upward movement of arms 49. Cam surfaces 53 also slide free of the cross members of chain 23 at the beginning of the upward movement of arms 49. The plates 54 are secured to a pair of laterally extending and vertically extending flange 55 for the purpose of limiting the side movement of arms 50 and 51. The plates 4 are secured to a pair of laterally ex-

tending bracket members 56 which are anchored to the side wall of casing 20. The foregoing features of the sterilizing tank are essentially the same as set forth in my Patent No. 1,988,963.

5 The discharge mechanism of the washing machine proper will now be described in order to show the synchronous movement of the sterilizing mechanism with that of the washing mechanism. A stud 57 which connects each connecting 10 rod 44 with legs 45 of bell cranks 46 also connects one end of a power link 58 and a power link 59, link 58 being the drive mechanism for the washing mechanism and 59 being for the feeding mechanism for the sterilizing machine. The opposite end of power link 58 pivots on a clamp pivot 60 which is suitably secured as by clamp bolts to a driving rod G-1 as may be clearly seen from Figs. 3 and 4. (Note: Throughout the following description, all of the operating mechanism is duplicated part for part on each side of the washing mechanism with the exception of the conveyor centering means, and for simplicity in description the parts will be described individually rather than in pairs.) Housing 20 carries a 15 guide bearing 61 for driving rod G-1 which in turn is also carried by guide bearing 62 on the rear wall 63 of the washing tank 64, which tank has a main front wall 65, auxiliary front cover wall 66, left side wall 67, and right side wall 68. 20 A bracket 63a is suitably secured to the rear wall 63 and to tank 20 and serves as a spacing and aligning brace for the washing tank and sterilizing tank. A rock arm F-1 has a pivot rod F-2 secured to a bracket 69 on each of the side walls 25 67 and 68, and arm F-1 is pivotally connected approximately midway between its ends to power link 59 and actuated thereby. The features now being described can be seen on the following figures: 1, 5a, 6a, 8, 8a, 9, 10, 11, 12, 29, and 29a. A 30 link F3 is pivoted to the upper end of rock arm F-1 and is connected by a stud F4 to a rocker arm F5, which arm rocks on a rear rock shaft F6, pivotally mounted in a slide bar F7 integrally secured to a cross plate F8. Slide bar F7 is slid- 35 able between upper and lower angular guide members F9 supported on the sides 67 and 68 of the tank 64. A front rock shaft F10 is rotatable in the forward part of slide bar F7 and carries a front rock arm F-11, to which is pivotally connected one end of a link F12, the other end of 40 which is connected to stud F4 of rocker arm 5. A block F13 is secured on plate F8 and provides a stop for the movement of link F12 such that the rock arms F5 and F-11 are permitted an angular 45 oscillation of forty-five degrees each way from the vertical and providing a ninety degree movement for rock shafts F6 and F10. The reciprocatory or oscillatory movement of rock arm F-1 produces a double result with respect to rock shafts F6 and F10. The forward movement of F-1, which will be considered to the right as seen in Fig. 1, will first cause rock arms F5 and F-11 to be rotated ninety degrees clockwise or to the right, and further forward movement of rock arm F-1 50 will move the entire assembly consisting of rock arms F5, F-11, slide bars F7, cross plate F8, block F13, and link F12 to the right a distance of approximately ten inches for a purpose which will be more fully apparent hereinafter. 55 50 A horizontal angle member 70 is secured on the inside of rear wall 63 of tank 64, and a pair of angle members 70a extend across tank 64 and are secured to side walls 67 and 68, as can be seen on Figs. 8 and 8a. A post 71 is mounted on angle member 70 and a post 72 is supported on the upper 55

member 70a. An angle member 73 extends longitudinally and is supported by posts 71 and 72, and a block 74 is secured on member 73. A friction catch 75 is located in block 74 and has the usual or any preferred arrangement such as ball 76, plunger 77, spring 78, and securing nut 79. For cooperative action with friction catch 75 an angle plate F14 is secured to cross plate F8, there being an aperture F15 in the upper extension of plate F14 for engagement with ball 76 of the friction catch 75. The action of this mechanism is such that when plate F8 is in its extreme position to the left, ball catch 75 will engage aperture F15 and retard any advance movement of plate F8 and members F7 and rock shafts F6 and F10 until the rock arms F5 and F-11 have been rotated clockwise ninety degrees, whereupon further forward movement of rock arm F-11 will cause members F5, F-11, F6, F10, F7, and plate F8 to be advanced and angle member F14 disengaged from the friction catch 75. Rock shaft carriers a number of spaced advancing fingers F16, there being one for each of the number of bottles which the machine is designed to accommodate at each cycle, which, in the example under consideration, is 4. Likewise, rock shaft F10 has a similar number of spring fingers F17 similarly spaced, the spacing being determined by the distance between the centers of the bottle feeding guides, to be more particularly described hereinafter. Cross bar 80 is supported at its ends on horizontal angle members 73, adjacent the end wall 63, and a plurality of blocks 81 are supported on the left end of members 73 at the point of support of member 73 on post 72. Cross bar 82 is mounted on blocks 81, and a plurality of horizontal angular track members F18 are mounted at the right end of member 80 and at the left end on F19 which is an inclined portion of F18 on cross bar 82. Members F18 are separated from each other to provide longitudinal slots in which the fingers F16 and F17 are adapted to be rotated and oscillated. The angle members F18 are adapted to form a trackway for the bottles which have been washed and are being transferred to the sterilizing tank 20. When rock shafts F6 and F10 are rotated clockwise as hereinabove explained, fingers F16 and F17 are rotated to a vertical position, and the advance movement to the right of shafts F6 and F10 will cause fingers F16 and F17 to push the bottles which are in the tracks or on the members F18 forward substantially the distance of the standard bottle, which, in the example shown, is a quart milk bottle. A U-shaped bottle chute 83 is provided for each of the trackways F18 and is mounted on post 71 and on the front wall of tank 20. A swinging chute 84 for the lower end of chute 83 is pivotally secured to the forward wall of tank 20 and is provided with an adjustable counterweight 85 as described in detail in said Letters Patent No. 1,988,963. Chutes 83 and 84 are adapted to discharge the bottles into bottle carrying cups 86 of the sterilizing mechanism in the housing 20 and tank 21, which bottle carrying cups are advanced by lever arms 50 and 51 as described in said Letters Patent. Plate F8 is provided with a bracket F20 for the pivotal support of trip finger F21, which in turn is provided with an adjustable tip F22, and is actuated from forward rock shaft F10 by a pin F23 such that the rotation of rock F10 will cause pin F23 to raise trip finger F21 an amount equal to the length of pin F23. This may be seen clearly from Figs. 8 and 12, and performs a function in connection with the dump-

ing elevator mechanism E to be described more fully hereinafter.

Referring now to Figs. 6a, 8a, and 28, the principal operating mechanism or reciprocating power frame G will be described. As stated above, a driving rod G-1 is mounted in guide bearings 61 and 62 and is pivoted by clamp pivot 60 to power link 58 and reciprocates forwardly and backwardly a stroke of approximately 18 inches, the forward stroke being to the right in the figures mentioned or to the rear part of the machine and away from the operator whose position is at the front of the machine in front of front wall 66, and the return stroke being considered to the left or towards the wall 66, and thus toward the operator. A pair of cross channel members G2 are suitably secured to the front end of rods G-1, the rods having reduced end portions G3 to receive a securing nut G4, and a side guide shoe G5 is secured at the ends of cross channels G2, the shoes G5 being adapted to reciprocate along longitudinal guide members 87 mounted on the rear portion of side walls 67 and 68 respectively. A bracket G6 is secured to the forward channel member G2 and held by nut G4 and serves to secure one end of push-pull drive rod G7 for the actuation of the idler carriage H to be described more fully hereinafter. Also secured to the forward channel member G2 is a bracket G8 forming a pivot for a link G25 presently to be described. Also suitably secured to the channel members G2 is a bracket G9 having a cam roller G10 and a resting shoe G-11 for a function in connection with the conveyor centering mechanism to be fully described hereinafter.

A rectangular frame G12 has an upper cross member G13 and lower cross member G14, the latter being secured to the rear cross channel G2. A plurality of upper ejector rods G15 are slidable in apertures G16 in the upper cross member G13 as shown in detail in Fig. 31, there being one ejector rod for each of the number of bottles to be moved in each cycle, which in the instant case is 4. Each rod G15 has a forward collared knob G17 and a rear collared knob G18. A similar plurality of lower ejector rods G19 are located in the lower frame member G14 and have forward collared knobs G20 and rear collared knobs G21. The lower ejector rods G19 are not slidable in their aperture mountings in member G14. As will be obvious from the description of the operation, these rods are fixed with respect to member G14. In Fig. 8 is shown a tie plate 88 having a front supporting member 89 which is mounted on upper angle member 70a and a rear supporting member 90 mounted on angle member 70. Plate 88 has an upwardly extending bracket portion 91 on which is mounted a spring clip 92 for each of the knobs G18 of rods G15, and a spring clip 93 for each of the knobs G21 is mounted on the rear wall 63.

The forward end of rod G7 has a flattened portion G22 (Fig. 6), there being a rounded shoulder G23 where the inner edge of end portion G22 merges with the inner edge of rod G7 and a shouldered recess G24 in the inner edge of G22. The forward end of link G25, hereinabove referred to, is pivotally connected to a rock arm G26 secured to a rock shaft G27, which extends across tank 64 and is mounted in bearings G28 on side walls 67 and 68, but which is shown with the central portion broken away in Fig. 6. A cam shoe G29 is secured to rock arm G26. A rock arm E-1 is secured to rock shaft G27 and is the

actuating member for the dumping elevator mechanism to be described hereinafter.

A motor D-1 (Figs. 6, 7, and 8) is mounted on a supporting plate D2, the forward end of which is mounted on an angle member D3, which is secured to front wall 65 and the rear portion is mounted on a supporting bracket D4, the ends of which are supported by track members 99. A forward channel member 94 and a rear channel member 95 (Figs. 8, 12, and 15) are mounted on side walls 67 and 68, and a front end channel member 96 is mounted on front wall 65 and provides a support for the spindle bearings about to be described. A supporting bar 97 is mounted on and secured to channel members 94, 95, and 96. A pair of trackway plates 98 is mounted on the supporting bar 97 and provides a lower trackway, and a pair of upper trackway plates 99 provides an upper trackway and is supported on a post 100, which in turn is supported by trackway plates 98. A plurality of bearing blocks 101 (Fig. 34) are mounted between a lower cross bar member 102, which is supported on plates 98, and an upper cross bar 103, extending between and secured to side walls 67 and 68.

A plurality of flange bearings D5 (Figs. 6, 8 and 34), are mounted on channel member 96, and each bearing provides support therein for the forward end of a hollow shaft D6, the other end being carried by one of the bearing blocks 101, each providing a bearing for the rear end of shafts D6. A packing seal D7 is provided between each shaft D6 and its bearing D5. At the extreme front end of each shaft D6 an actuating sprocket D8 is mounted, and a pair of chains D9 connect alternate shafts D6 with a motor shaft sprocket D10. A plug D11 is provided to seal the front end of each shaft D6. The shaft D6 is provided with a pair of longitudinal slots D12 approximately ten inches in length, and an auxiliary tubular shaft D13 is arranged within shaft D6. A stud D14 extends through each slot D12 and is secured to shaft D13 and carries a sleeve D15 and a cam roller D16 suitably positioned so as to be maintained outside of the slot D12. A recessed plug D17, which can be seen more clearly in Fig. 36, is located in the rear end of shaft D13 and has a hollow tapered cylindrical recess D18 adapted to receive and retain a rubber friction plug D19. The plug D17 is provided with a slot D20, and pin 21 is secured in shaft D13 and extends into slot D20. A ring D22 is provided on shaft D13 to retain pin D21, and a stop ring D23 is suitably secured to shaft D13. Adjacent the end of shaft D13 is a flared collar D24 adapted for moderate slidable movement on shaft D13, and a stop ring D25 is secured at the end of shaft D13 to keep collar D24 on the shaft. A coil spring D26 seats against collar D24 and maintains ring D22 against stop ring D23. A compression power spring D27 (Figs. 12 and 34) is maintained within shafts D6 and D13 and presses against plugs D11 and D17. The foregoing structure is such that when the shafts or spindles are rotated by the sprockets D8, the inner shaft D13 carrying the plug D17, and the associated parts may be retracted, that is, moved to the left, compressing spring D27, by the same actuating means which removes the bottles from the conveyor C, a distance of approximately nine inches or the length of the largest size bottle to be used, and returned by spring D27 upon the retraction of the said means by mechanism hereinafter to be described.

The idling pick-up power carriage H about to be described, consists generally of an auxiliary

frame arranged to be actuated mainly by the reciprocating power frame G but adapted to be disengaged therefrom during a portion of the stroke of the frame G, and is most clearly shown in Figs 14a and 25 but is also shown in Figs. 6, 8, 13, 14, 15, and 24. A plurality of collars H-1 are provided, there being one for each spindle or shaft D6 and located near the front ends of the shafts. Collars H-1 are secured to upper 10 and lower cross bar supporting members H2, each of the bars H2 having secured thereto, adjacent the ends, an L-shaped shoe plate H3 adapted for slidable movement between trackway members 98 and 99. A post member H4 is secured between and serves to space and position upper and lower plates H3. To each of the plates H3 is secured a side guide plate H5 adapted to serve as a guide member for the movement of bars H2 along trackway 98 and 99. An auxiliary cross bar H6 extends substantially the length of upper cross bar H2 and is secured thereto and has a bracket portion H7 adapted to provide a bearing for a stud H8, which carries a slide link A-1 and link B-1, hereinafter to be described. 15 At each end of members H2 is secured a block H9, each providing a bearing for a guide roller H10, and a plate H-11 is secured between and interconnects the ends of upper and lower cross bars H2. Guide roller H10 is adapted to roll along the outer edge of drive rod G-1 hereinabove described. Upper and lower members H3 each are provided with an outwardly extending bar member H12 (Figs. 24 and 25), the outer ends of which are interconnected by plate H-11. 20 A roller H13 is maintained between bars H12 and is adapted for roller action along the inner edge of the flattened end G22 of shaft G1. 25 At each end of members H2 is secured a block H9, each providing a bearing for a guide roller H10, and a plate H-11 is secured between and interconnects the ends of upper and lower cross bars H2. Guide roller H10 is adapted to roll along the outer edge of drive rod G-1 hereinabove described. Upper and lower members H3 each are provided with an outwardly extending bar member H12 (Figs. 24 and 25), the outer ends of which are interconnected by plate H-11. 30 A roller H13 is maintained between bars H12 and is adapted for roller action along the inner edge of the flattened end G22 of shaft G1. 35 A roller H13 is maintained between bars H12 and is adapted for roller action along the inner edge of the flattened end G22 of shaft G1.

A pick-up and release mechanism designated generally by H14 is shown particularly on Figs. 40 14a and also 24 and 25, and consists of upper and lower slidable blocks H15 adapted for slidable action along the inner surface of cross bars H2 and are provided with a spacing post H16 and an end plate H17, there being a pair of lower guide plates H18 and a U-shaped bracket and guide member H19 for the upper bar H2, and roller H20 is maintained between blocks H15 and is adapted for roller action along the entire inner edge of drive rod G1 and end portion G22 and is adapted to seat in recess G24 and be actuated by shoulder G23. A roller H21 is stud mounted on top of bracket H19, and a spring H22 is maintained under compression between post H16 and outer collar H-1. 45 A cam bracket 104 is secured to upper cross-bar member 103 hereinabove referred to, and has an offset inclined shoulder 105 in the line of travel of the roller H20. Interposed between plates 106 is a kick-back lever 107 pivoted thereto by pivots 108, and a roller 109 is provided at the end of one arm of the lever 107, and a roller 110 (Fig. 27) is provided with an eccentric mounting for adjustability on the end of the other arm of lever 107. A plate 111 having apertures for each of the shafts D6 is loosely mounted thereon and is secured at each end by a pair of springs 112 to bars 102 and 103, by which it is normally maintained against roller 110 and is so positioned on shaft D6 that contact is made with rollers D16 at the end of their forward movement when carried by shafts D13. 55 60 65 70

As stated hereinabove, drive rod G1 being fixed to drive rod G-1 has a forward and return stroke of approximately eighteen inches, the forward stroke being to the right as viewed in Figs 1, 75

14, and 24. When the rod G7 is in its extreme forward position, roller H20 will be opposite and drop into recess G24 by action of the spring H22 pressing against pick-up and release mechanism H14. The return stroke will thereupon carry the entire carriage H with it until near the end of the return stroke, whereupon roller H21 will pass over cam shoe G29, which will force the pick-up and release mechanism H14 to be disengaged from recess G24, and further return movement of the power carriage H will not occur. However, movement of drive rod G7 will be continued to the position shown in Fig. 6, and the pick-up and release mechanism will pass the shoulder G23, and roller H20 will rest against rod G7. Upon the start of the forward stroke of rod G7 the pick-up carriage H will be carried forward inasmuch as roller H20 is held against shoulder G23 and carried by it. When the roller H20 passes inclined shoulder 105 the release mechanism H14 will be pressed inwardly and freed from shoulder G23, which will stop the forward movement of the carriage H, which will thereupon be in the position shown in Fig. 14. In this position the rollers D16 will be pressing against plate 111, which is in the position shown in Fig. 6, and the position of arm 107 can also be seen in Fig. 6 with roller 109 against rod G7. The rod G7 will continue its forward movement, but at this instant the shoulder G23 is about to engage roller 109, and as the rod G7 continues its movement, roller 109 will be forced past shoulder G23 and onto flattened portion G22, which will cause the lever arm 107 to be rocked, causing roller 110 to force plate 111 to the left or away from bars 102 and 103, carrying with it rollers D16 and the shaft D13. The movement of plate 111 is a small amount, approximately one and one-quarter inches. The mechanism will then be in the position shown in Fig. 24, and further forward movement of rod G7 will cause roller H20 to drop into recess G24 as already explained, completing the cycle.

Referring now to Fig. 16 and the pivoted feeding table mechanism B, a link B-1, as hereinbefore stated, is pivoted to stud H8 on bracket H7, and is pivoted at its other end to a rock arm B2. A stud 113 is mounted in a bearing 114 on a supporting plate 97 and forms a pivot for rock arm B2. A roller B3 is pivoted at the upper end of rock arm B2. Bearings 115 are mounted in side walls 67 and 68 and each is provided with a stud 116 on which a bracket B4 is pivotally connected. A cross channel member B5 is secured to and supported by the opposite bracket members B4, and an arcuate rock arm B6 is secured thereto and has a straight portion B7 and an arcuate shoe portion B8. A cross plate B9 is secured on the upper side of channel member B5 and supports a plurality of guide angles B10, there being two for each bottle channel or eight for four channels, the capacity of the present embodiment of my invention. A rear guide shoe B11 is secured at an angle to the under side of the one edge of plate B9. Resilient strips 117, one for each bottle channel, are supported at their lower ends on lower angle member 70a and at their upper ends on shoe member 89 (Fig. 8). Mounted on the sides of the outer two guide angles B10 is a housing B12 which is provided with an upper pivot B13 and a lower pivot B14, the upper pivot carrying an upper centering clamp arm B15 and the lower pivot carrying a lower centering clamp arm B16. One end of a bearing shaft B17 is carried by the rear

end of centering clamp arm B15, and one end of a lower bearing shaft B18 is carried by lower clamp arm B16. Shaft B17 carries a plurality of upper centering rollers B19 having concave portions opposite each bottle channel, and a similar plurality of lower centering rollers B20 are similarly mounted on shaft B18 and have similarly positioned concave portions. Appropriate spacing collars B21 (Fig. 19) are provided between adjacent rollers B19 and B20. A stop roller B22 is provided at each end of shaft B17, and a stop bracket 118 is mounted on member 70a. A spring B23 is suitably secured between arm B15 and portion B8 of arm B6. At the forward end of arm B15 is an angularly projecting lug B24, and a similar lug B25 is secured to arm B6 (Fig. 16). A stop block B26 is located on the front wall of housing B12 opposite lug B25. An angle member B27 is secured to bracket B4 for a purpose in connection with the lifting of the dumping elevator mechanism E, to be described fully hereinafter.

A tilting of the pivoted feeding table B is accomplished by the operation of gravity, the center of gravity being such that it will normally assume the position shown in Fig. 12. Roller B3 has a path along rock arm B6 which includes the straight portion B7 and the arcuate portion B8 so that the first portion of the forward movement of rock arm B2 will swing table B from the position shown in Fig. 12 to that shown in Fig. 13. Further forward movement of arm B2 will cause roller B3 to move along the arcuate portion of B8, the arc center of which is stud 113, and no further movement of the table B will occur. Upon the return stroke of the arm B2 the table B will be caused to drop to the position shown in Fig. 12, whereupon roller B22 will be engaged by bracket 118 prior to the completion of this movement, and centering rollers B19 and B20 will be separated to permit the neck of a bottle to be passed therebetween, the closing action of the rollers occurring when the table B is rotated to the horizontal position, the spring B23 causing the arm B15 to be swung toward arm B16, the lug B25 being actuated by the lug B24 such that the rollers B19 and B20 firmly engage the neck of a bottle as shown in Fig. 13. After the table B has been swung to the horizontal position and after the bottles have been transferred to the conveyor in a manner to be described fully hereinafter, the rollers B19 and B20 will be maintained in a position spaced apart a small amount by the stopping of lug B25 against block B26 and the stopping of lug B24 against lug B25, as shown in Fig. 14. This is to permit the contact head A32 of a finger bolt A31 to be passed therebetween, as will be clear hereinafter.

The dumping elevator mechanism E will now be described, parts of which are shown in Figs. 1, 5, 6, 7, 8, 12, 13, 14, 15, 19, and 30. A rock arm E-1 (Fig. 1) is secured to shaft G27 and is pivotally connected at its free end with a link E2 which in turn is pivotally connected to a stud E3 (Figs. 19 and 30) in a reciprocating block E4 adapted to slide in a pair of slide shoes E5 in a groove E6 of an elevating member E7. The member E7 has a pair of resilient clamping portions E8 which form an aperture E9 for a rotatable shaft E10 which extends across the tank 64, and block E4 has a semi-circular recess E11 adapted for periodic engagement with the end E12 of shaft E10. Side walls 67 and 68 of tank 64 are each provided with a slot 119, the bottom of the slot 119a, serving as a rest for shaft E10 during a portion of the cycle of operation of the machine. A

channel member 120 is secured by side angle members 120a to side walls 67 and 68 on either side of slots 119, and forms a double guide track for block E4 and elevating member E7. A disk E13 is secured to shaft E10, and has its outer edge adapted for contact with angle member B27. A cross supporting plate E14 (Fig. 13) is provided adjacent its outer ends with a pair of downwardly extending angle members E15 which are pivoted to shaft E10 utilizing a hub E16 for this purpose. An apron member E17 extends downwardly from the rear edge of plate E14 and a pin E18 extends outwardly from each angle member E15 and is adapted to lodge against the upper end of a V-shaped recess E19 in the lower side of a block E20 which is secured to the shaft E10. A spring arm E21 is suitably clamped to block E20 and has secured to its outer end one end of spring E22, the other end of which is secured by a pin E23 to a post E24 which is mounted on the supporting plate E14. A pair of angle members E25 (Fig. 5) is provided for each bottle channel, of which there are four as hereinabove mentioned, members E25 being spaced apart and secured on top of the cross supporting plate member E14. A pivot E26 is provided by the adjacent angle members E25 of adjacent bars, and each pivot E26 pivots a rock bar E27, the rear end of each of which rests on and is operated by a kick-back plate E28, there being a plurality of recesses E29 in plate E28, one recess being in each bottle channel and adapted for engagement with the neck of a bottle (Fig. 13a). A tilting arm E30 (Fig. 14) is pivoted at E31 to a lug E32 on the outer end of plate E14, and an upwardly extending trip arm E33 is secured to the arm E30. An extension arm E34 is secured on plate E28 (Fig. 19) and is adapted for periodic engagement with a stop member E35 mounted on the block 81, which as hereinbefore stated is secured on fixed angle member 73. Angle members E25 are provided with chamfered corners E36 to provide clearance for contact heads A32 of finger bolts A34 as will be apparent more fully hereinafter.

The operation of the dumping elevator mechanism E is as follows: When the rock arm E-1 is in the position shown in Fig. 1, block E4 and elevating member E7 are in their lowermost positions, and shaft E10 will rest on bottom 119a of the slot 119. Recess E11 will be considerably below shaft E10 at this moment, and the dumping elevator E will be in the position shown in Fig. 3. As arm E-1 is rocked upwardly, block E4 is started on its upward movement. At the same time rock arm B2 is being rotated to the right (Figs. 8 and 12) and with roller B3 engages straight portion B7 of rock arm B6 and rotates the pivoted feeding table B from the inclined to the horizontal position shown in Fig. 13. In the rotation of table B as described, angle member B27 will engage the edge of disk E13 which will cause shaft E10 to be raised from its position on the bottom 119a of the slot 119 to the position shown in Fig. 19. This results in the elevator E being raised to the position shown in Fig. 13, where it stops for an interval of time, this being considered its intermediate position. Further movement of rock arm E-1 raising block E4 will cause the latter to engage the end E12 of shaft E10 by the shoulder E11 of block E4 engaging the end E12. Further movement of rock arm E-1 and block E4 will raise the elevator mechanism by shaft E10 to the dotted position shown in Fig. 14. Just prior to the completion of the elevation of shaft E10, extension E34 will be engaged by stop member E35,

causing the elevator E to be tilted or rocked on the shaft E10, the pin E18 being rotated downwardly out of the recess E19 in the block E20. This is the position of the elevator at the end of the forward stroke of the drive rod G-1.

On the beginning of the return stroke the movement of the parts is substantially in the reverse order to what has just been described, except that the intermediate position of the elevator is maintained only momentarily before being lowered to the initial position as shown in Fig. 12.

Referring now to the feeding advance mechanism A, which may be seen on Figs. 5, 14, 16, 17, and 18, the slide link A-1 as stated hereinabove is adapted for slidable engagement by slot A-2 with a stud H8 on the idling pick-up power carriage H, the stud extending through the slot A-2. The link A-1 is pivotally connected at its opposite end with a rock arm A3 on stud 113, as hereinabove referred to, there being a slot A4 in the upper end of rock arm A3 adapted for slidable engagement with a stud bolt A5 in a block A6 (Fig. 17). A pair of bracket plates A7 is secured to block A6, and a pair of side guide bars A8 is secured to plates A7 and they are adapted for slidable engagement with a fixed track bar 121, which is secured at its rear end on post 72 and at its front end on an angle member 122 secured on front wall 66. A roller A9 is secured between plates A7 above track bar 121, and a pair of auxiliary bracket members A10 is secured across side guide bars A8. A follower rail A11 is secured at one end to the lower end of bracket A10 and at the other end to a pair of brackets A12 secured to the forward end of guide bars A8. From an inspection of Fig. 16 it will be obvious that shaft G27 extends across tank 64 between members A8 and A11. A plate A13 is secured to the outer side of each guide bar A8, and a roller A14 is secured below roller A9 and track bar 121 and between brackets A10. A pair of rollers A15 is secured between pairs of plates A13 above track bar 121. A pin A16 (Fig. 17) is secured on the rock arm A3 and secures one end of a spring A17, the other end of which is secured to an eyelet A18 on front wall 65. A rock shaft A19 is secured to and between the pairs of plates A13, and a rectangular block A20 is secured to shaft A19 between each pair of plates A13 on the right and left hand sides of the machine respectively. Each block A20 has a square surface A21 and a second square surface A22. A leaf spring A23 is secured to a block A24 which is mounted between each pair of plates A13, and a lever arm A25 is secured at some convenient point on the shaft A19, the lever arm being adapted to strike against shaft G27 for the rotation of shaft A19 a quarter turn when the feeding advance mechanism A is advanced during the cycle of operation. A stop bar 123 is mounted on angle member 122 in the pathway of lever arm A25 and adapted to turn shaft A19 a quarter turn in the reverse direction from that caused by contact of arm A25 with shaft G27. A cross bar 124 is secured to the upper side portion of angle member 122, and a cross bar 125 is secured across tank 64 and is secured to sides 67 and 68 respectively (Figs. 5, 8, 14, and 16). A plurality of plates 126 are secured adjacent each other between bars 124 and 125 and together serve as the bottom plate of the feeding table, there being slots 127 in the adjacent edges of plates 126. A plurality of guide blocks 128 are provided in pairs (Fig. 7) and mounted on plates 126, forming a plurality of guide channels for the initial advancement of the bottles into the machine. A plurality of fingers

A26 are secured to shaft A19, one finger adapted to extend upwardly through each slot 127 when the shaft A19 is in the position shown on Figs. 5 and 16, and to extend horizontally below slots 127 when shaft A19 is in the position shown in Fig. 14. A pair of loading platforms 129, one on each side, is detachably secured to cross bars 124 and 125 and also supported at the outer side on an angle member 130 secured to sides 67 and 68 respectively. A bracket A27 is secured to the upper end of each bracket member A7, and a cross bar A28 is secured between the two brackets A27. A plurality of finger arms A29, one for each bottle channel, are secured to bar A28, and each arm A29 is provided with a rearwardly extending sleeve A30, in which is resiliently mounted a slide bolt or finger A31 having a contact head A32 and secured by an adjustable lock nut A33, a spring A34 being positioned between the contact head A32 and arm A29.

The feeding advance mechanism A is actuated by the arm A3 under the influence of link member A-1 when reciprocated by stud H8 of the idling pick-up power carriage, the stud bolt A5 causing the frame members A8 and A11 to be reciprocated forwardly or to the right and returned, the forward movement causing bottles in the bottle channels to be advanced by fingers A26 and the fingers A31 causing the transfer of bottles from pivoted feeding table B past the rollers B19 and B20 into the conveyor about to be described. As stated above, lugs B24 and B25, together with stop lock B26, are adapted to maintain rollers B19 and B20 separated a sufficient amount to permit the fingers A31 and contact head A32 to pass therebetween, as may be clearly seen from Fig. 14. When the lever arm A25 strikes shaft G27, shaft A19 is rotated a quarter turn, causing the fingers A26 to be rotated to the horizontal position, and when the A frame is returned to the front of the machine by the return stroke, the arm A25 strikes stop bar 123 and rotates shaft A19 a quarter turn to its original position, raising fingers A26 vertically for engagement with the next succeeding group of bottles to be advanced. Also on the return stroke, arm A3 is returned toward the front end of the machine by action of spring A17 as fast as permitted by the movement of link A-1 as frame H is returned.

The conveyor mechanism C, which is best shown on Figs. 1, 3, 4, 5a, 6a, 9, 10, 11, is operated from clamp pivot 60 on driving rod G-1 and power link 58, having a yoke C-1 connected to clamp pivot 60. Right and left hand drive bars C2 are respectively connected to yoke C-1 and are provided with an angular track C3 secured on the outsides of sides 67 and 68 of tank 64. A cover and guide member C4 is provided for each track C3, there being lower and upper side extensions C5 and C6 respectively for cover member C4. A V-shaped cam shoe C7 is formed as a part of the left hand drive bar C2, and a similar cam shoe C8 is similarly formed as a part of right hand drive bar C2. The cam shoe C7 has a cam edge C9 and cam shoe C8 has a cam edge C10, these cam edges being substantially parallel and directly opposite each other. Cam shoe C8 is also provided with an outer edge portion C11, the importance of which will be apparent hereinafter. A pair of power cross bars C12 spaced by driving bars C2 is mounted on bearing brackets C13 on the rear end wall 63, and at the left end of bars C12 a cam roller C14 is secured therebetween and at the right end a cam roller C15 is similarly positioned (Fig. 9). A pivot block C16 is secured to

bars C12 at a selected point between brackets C13, and a link C17 is pivoted at one end to the pivot block C16 and at the other end to the lower end of a rock arm C18, which in turn is pivoted at C19 to the rear wall 63 of tank 64. A drive shaft C20 is mounted in a fixed rear bearing C21 on wall 63, and a fixed forward bearing C22 mounted on angle member 70a (Fig. 10). An idler shaft C23 is mounted on a rear adjustable bearing C24 on wall 63 having an adjusting screw C25 and on a front adjustable bearing C26 mounted on angle 70a having an adjusting screw C27. A front and rear sprocket C28 are secured on each shaft C20 and C23, and a chain C29 is adapted to be carried by the front sprockets and a second chain C29 carried by the rear sprockets, the chains C29 each having links C30, each link having an inner and outer member, between which are a plurality of guide and support rollers C31. Guide rollers C31 are adapted to pass over and be supported by tie plate 88 during the upper portion of the travel of the chains.

A gear C32 is keyed to shaft C20, and a stud bolt C33 secured to wall 63 is provided for an idler gear C34, idler gear C34 having its teeth engaging teeth of gear C32. A ratchet wheel C35 is mounted on the outer face of gear C32 and has a plurality of teeth recesses C36. A ratchet wheel C37 is similarly secured on idler gear C34 and has a plurality of teeth recesses C38, however, being formed in the reverse direction from teeth recesses C36. A left hand pawl link C39 and a right hand pawl link C40 are pivotally connected to the end of upper arm C41 of rock arm C18. The outer ends of pawl links C39 and C40 are each provided with a ratchet tooth engaging roller C42.

The mechanism just described is actuated in conjunction with drive shaft G-1 by the reciprocation of drive bars C2, such that near the end of the forward stroke of G-1, cam edge C9 will engage roller C14, causing cross bars C12 to be moved to the left side of the machine, which is to the right as viewed in Fig. 9, at which time roller C15 will pass over edge portion C11 of cam shoe C8, the forward stroke of rods C2 ending with the roller C14 near the outer end of cam edge C9. This movement of cross bars C12 will be transmitted through link C17 to rock arms C18 and C41 and will cause a rotary movement of shaft C20 by gear C32 an amount substantially equal to the angular displacement of two of the ratchet teeth C36. This will cause the movement of chains C29 on sprockets C28 by an amount equal to two bottle carrier brackets, to be described hereinafter. At the beginning of the return stroke of drive rod G-1 and consequently the return stroke of drive bars C2, cam edge C10 will at once engage roller C15, which at this moment is in close proximity to the edge of right hand bar C2, and the return stroke will cause roller C15 to be pushed to the right as seen from the front of the machine (which is to the left as viewed in Fig. 9) until it reaches the edge C11, whereupon movement of the bars C12 will stop although further movement of drive bars C2 occurs. This reverse movement of bars C12 will cause rock arms C18 and C41 to be swung back to the original position, as shown in Fig. 9, whereupon ratchet tooth C42 of pawl link C40 will engage one of the ratchet teeth C38, causing a rotary movement of gear C34, which now drives gear C32 an amount equal to the previously described movement of gear 32 and shaft C20, the shaft C20 being moved in the same direction as before. By

this movement the chain C29 will again be advanced a distance equivalent to two carrier brackets as before, making a total of four, which is equal to the total number of bottle channels or the number of bottles to be progressed during each cycle of operation of the machine.

The outer member of each link of chains C29 has secured to it by bolts a carrier bracket C43 (Figs. 40, 41, and 42). Each bracket has a shoulder C44 and a corner abutment C45. Between opposite pairs of brackets C43 is located and secured thereto a bottle carrier C46, which is a hollow tube of sufficient length to receive the largest size bottle for which the machine is designed, which in the instant case is a quart milk bottle having a height or length slightly over nine inches. A brush bracket C47 is secured to each of the rear chain links C30, members C47 having a pair of apertures C48 adapted to receive a pair of slides rods C49 which are secured as by threaded bolts into a bearing block C50 which is cylindrical and located within each of the carriers C46. Each bearing block C50 has a central circular aperture C51, substantially the interior diameter of the bottle neck. A ring bearing having a fixed half portion C52 is located at the outer side of block C50, and a rotatable half C53 is held by retaining ring C54 which has a conical centering surface C55 and is secured to block C50 by a pair of bolts C56 which also secure a pair of spring clips C57 to block C50 and have a shoe portion C58. These parts can also be seen in part in Figs. 36 and 37.

A slideable yoke C59 has a pair of apertures C60 through which rods C49 are adapted to reciprocate and a central aperture C61. A spring clip C62 having an engaging edge C63 adapted to engage collared knobs G17 and G20 hereinabove described, is secured to the free end of each rod C49, and a coiled compression spring C64 is located on each rod C49 between yoke C59 and spring clip C62. It will be apparent that the springs C64 are adapted to provide a resilient limit for the movement of the rods C49 in their movement towards the front of the machine.

Referring now to Fig. 28, a bracket C65 is secured on the inside of side wall 67 and is provided with a pivot C66 and an abutment C67. A rock arm C68 is pivoted on pivot C66 and has a lever arm C69 pivotally connected to a link C70. The arm C68 has a curved counterweight arm C71 provided with a counterweight C72 and a cam surface C73. A slideable bar C74 (Figs. 21, 22, and 28) is pivotally connected to link C70 and is mounted between a pair of guide blocks C75, which are secured to the inner side of side wall 67, and a pair of guide plates C76 is secured to guide blocks C75. A lug C77 is formed at the upper end of bar C74 and provides a pivot connection for an adjustable link C78, the opposite end of which is provided with a pivot C79, by which it is secured to a pivoted centering shoe C80, which in turn is pivoted on a pair of eye-bolts C81 also secured to wall 67. A stop bracket C82 is also secured to one of the guide plates C76 and provides an upper stop limit for the swinging movement of centering shoe C80, as shown in dotted lines in Fig. 21. The centering shoe C80 is located on wall 67 directly opposite the path of carriers C46 and is adapted to move the carriers a small amount for centering the conveyor, as will be apparent hereinafter.

A back dash block C83 (Fig. 23) is secured on the inner side of side wall 68 and has a bore C84, in which is mounted a reciprocable plunger C85, 75

its position being adjustable by a nut C86, and a spring C87 is located in bore C84 and is adapted to retain the plunger C85 in its lowermost position. The plunger C85 is provided with a pivot 5 C88, by which a stop arm C89 is secured thereto, said arm having an abutment C90 adapted for engagement with corner abutment C45 of shoulder C44 on each of the carrier brackets C43. Arm C89 has an elongated slot C91, through which passes a guide pin C92, which is secured and locked on wall 68, and a spring C93 is mounted on pin C92 between arm C89 and wall 68.

The operation of the foregoing described mechanism is such that when the conveyor has been brought to a stop after a movement by the gears C32 and C34, the bottle carriers C46 will be approximately in alignment for receiving bottles from the pivoted feeding table B and to discharge bottles to the elevator mechanism E and also for removing the bottles from the lower portion of the conveyor for the washing operation by the spindles D. In order to insure the precise centering of the bottles for these operations, after the conveyor has stopped as aforesaid, the return movement of drive rod G-1 (Fig. 28) will cause roller G10 to engage cam surface C73 of rock arm C68 which was in the dotted position shown in Fig. 28 and centering shoe C80 was in the dotted position shown in Fig. 21. As the roller G10 moves to the left, arm C68 will be rocked to the position shown in full lines in Fig. 28 and resting shoe G11 will come to a stop in the position shown in Fig. 28. This movement will be transmitted through link C70, bar C74, and link C78 to centering shoe 30 C80, which will be transmitted to the adjacent carrier C46, moving the carrier and the conveyor an amount necessary to bring corner shoulder C45 of the carrier on the opposite side in engagement with abutment C90, the position of which by adjustment with adjusting nut C86 will insure the conveyor carriers C46 to be in precise alignment for the bottle transfer operations just mentioned.

Referring now to Fig. 10, a pair of cross guide 45 track members 131 is mounted on supporting bars 97 and provides a guide track for shoulders C44 of carrier brackets C43 when the brackets are in the lower portion of their path. A pair of semi-circular guide plates 132 is secured on angle members 70a, and their purpose is to prevent the accidental removal of bottles from the carriers C45 except when in the central positions, as should be obvious.

Referring again to Figs. 31, 32, 36, 37, 38, and 55 39, the inside bottle brushing mechanism will now be described. A brush supporting post C94 having a threaded portion C95 is secured as by a lock nut C96 on each brush bracket C47. A pair of parallel slots C97 is provided in each post C94, and a stud pivot C98 provides a pivot mounting for a pair of brush holder rocker arms C99. Each rocker arm C99 is provided with a cam arm C100 and a clip arm C101 (Figs. 38 and 39). Clip arm C101 is formed at an angle with cam arm C100. The rocker arm C99 is, for convenience, constructed of a pair of resilient steel strips suitably riveted together along the cam arm portion, but sprung apart slightly at the clip arm portions, which are provided with flares C102 and a lock pin C103. An aperture C104 is formed in each portion of the clip arm C101 near the extreme end. The pairs of rock arms C99 mounted in each post C94, while identical in structure, are mounted in an opposite arrangement, such that when the cam arms C100 are

parallel, as in Fig. 37, the clip arms C101 will form an angle; and conversely, when the clip arms C101 are parallel by virtue of the operating movements to be hereinafter explained, the cam arms C100 will form an angle.

Referring now to Figs. 42-48, inclusive, each clip arm C101 is adapted to secure a detachable brush holding unit C105, each of which consists of a clip bar C106, which has a tapered end C107, which has an end slot C108 adapted for engagement with lock pin C103, each bar C106 also having a reduced end portion C109 in which is an aperture C110, and a tapered end pin C111 extends through bar C106 and is adapted for engagement with apertures C104. A pair of bristle clamp members C112 are each provided with an elongated pocket C113 adapted to receive reduced end portion C109 of clip bar C106 and a circular pocket C114 adapted to receive and secure a clump of bristles C115, which are formed in flat or fan shape. A countersunk screw C116 is adapted to pass through aperture C110 and secures one end of clamp members C112 to end portion C109 and clip bar C106, and similarly a countersunk screw C117 secures together the opposite end of clamp members C112 and secures the bristle clump C115 therebetween. Each cam arm C100 is provided with a curved cam surface C118 (Fig. 38) for occasional engagement with shoe portion C58 of spring clip C57 and additional cam surfaces C119 and C120. A portion of clip arm C101 is adapted to provide a cam surface C121 as will be explained hereinafter.

As the bottle enters the carrier C46, as from the position in Fig. 31 to that shown in Fig. 36, the bearing block C50 is carried rearwardly or to the right and the bristles C115 enter the neck of the bottle, and as the block C50 is carried to the right the shoe portion C58 of spring clip C57 moves from cam surfaces C121 over cam surfaces C118, C119, and C120, respectively, which movement causes the angularly positioned cam arms C100 to be brought into parallelism, which causes clip arms C101, which have been parallel, to form an angle, separating clip arms C101 from parallel position, one of the bristle sets C115 being lodged against one of the inner sides of the bottle and the other bristle set C115 being lodged against the diametrically opposite inner side of the bottle. This describes the action when the largest sized or quart bottle is thus transferred into the carrier C46. Upon the discharge of the bottle from the carrier C46, the reverse movement takes place, block C50 being moved to the left, shoe portions C58 passing over cam surfaces C119 and C118, and the bottle neck passes over cam surfaces C121 and partially draws them toward each other, bringing the clip arms C101 partially into parallelism as the bottle neck passes the bristles C115. At the extreme movement of block C50 to the left, the shoe portions C58 will pass over cam surfaces C121, bringing the clip arms C101 into substantial parallelism and causing the cam arms C100 to be separated or form an angle.

As stated above in connection with the operation of the A frame, bottles are transferred from the swinging carriage B by the fingers A31 into the conveyor carrier C46, the fingers A31 pushing against the bottoms of the bottles. The mechanism of this invention is such that bottles of different sizes can be accommodated without any adjustment; for instance, the machine is capable of washing pints and half pints, as will be clear from the following: Fig. 40 shows a pint

bottle in position in one of the carriers C46 and Fig. 42 shows a half pint bottle similarly positioned. In each of these two cases the bottle is pushed into the carrier C46 until the bottom of the bottle is just within the carrier. The action of the fingers A31 against the bottom of the bottle is such that the bottle pushes block C50 carrying the spring shoes C58. In the case of the pint bottle (Fig. 40), spring shoes C58 will have been pushed over cam surfaces C118 and C119 but will not have been passed over cam surfaces C120. The effect of this limited movement is that the clip arms C101 will make an angle as before but the angle will be smaller than in the case of the quart bottles. Brushes C115, however, will be firmly pressed against the opposite interior portions of the bottle for a thorough cleansing. The opening of the clip arms C101 will also raise a pint bottle off the bottom of carrier C46 and maintain it suspended in the center of the carrier in order that the proper engagement may be made with spindle members D19 and D24. The pint bottle is removed from the carrier in a manner similar to that of the quart bottle, the neck of the bottle passing over cam surfaces C121, drawing the clip arms partially together, which are finally closed by spring shoes C58 inasmuch as the bottle necks of both the pint and half pint are substantially the same size as that of the quart bottle. The half pint bottle as shown in Fig. 42 is similarly inserted and centered in the carrier C46, the movement of block C50 being such as to pass the spring shoes C58 over cam surfaces C118 only.

Referring now to Figs. 12 and 19, a pair of posts 133 mounted at the rear ends of upper track members 99 support the front end of an open frame 134, the rear portion of which is secured by a channel member 135 to lower angle member 10a. A plurality of depending hangers 136 are suspended from frame member 134, and each has a slot 137. Between each pair of front and rear hangers 136 is mounted a shaft 138 which carries a cylindrical brush 139, which are positioned by hangers 136 so as to come in contact with two adjacent bottles, except, of course, for the end brushes of the group which only contact one bottle. Tank 64 is provided with a bottom plate 140, and suitably positioned beneath each bottle, in the position of Figs. 12 and 19, is an elongated flanged base member 141. Member 141 has a plurality of cylindrical columns 142, one beneath each bottle, the columns each being provided with a bore 143 and an elongated slot 144 in one side. A pedestal member 145 is located in the bore 143 and has a base portion 146 supported by a spring 147, there being a pin 148 extending from the base 146 into slot 144 in order to prevent rotation of pedestal 145. An elongated scraper member 149 is secured to pedestal 145 and has a curved base 150 to facilitate the passage of bottles into and out of position. Scraper member 149 may be of any suitable scraping or abrasive material, or even have a cutting edge, as may be desired, and may be made of rubber, metal, or other suitable material for the purpose, being intended to remove the foreign particles or material such as old labels from the outside of the bottles when being rotated by the spindles D.

The operation of my invention as a whole is as follows: As stated above, all the operating parts with the exception of the spindle drive are operated from the reciprocating power frame G which has a stroke of approximately eighteen

inches. It is thought that a clear understanding of the interrelated movements of the various special units can best be obtained by comparing the movements of the sub-units with the movements of the power frame G as a base or standard. The forward stroke of the frame G, as stated above, is considered to be from the front toward the back, or to the right in the side views of the drawings, and the return stroke is from the rear toward the front or to the left. The spindles D are in continuous rotation during the operation of the machine, having a separate power, the motor D-1. A cycle of operation is considered to begin with the start of the forward movement of the power frame G and to be complete upon the end of the return movement of the said frame, which is the position shown in Figs. 8 and 8A.

The operation of introducing bottles into the machine is started by placing bottles on the feeding table 126, and it will be assumed that four bottles are so placed. During the first part of the forward movement of the power frame G a distance of approximately four and one-half inches, the pivoted feeding table B is rotated from the inclined to the horizontal position shown in Fig. 13, and during the next succeeding movement of the G frame of about four inches, the bottles will be transferred from the feeding table 126 to the left hand end of the pivoted table B. This movement will be caused by the fingers A26, being carried by shaft A19 on the A frame, pushing against the bottom of the bottles to complete this transfer. At this point the fingers A26 have been rotated horizontally by the contact of lever arm A25 with shaft G21, and at this point the forward movement of the A frame has stopped by the release of the idling pick-up power carriage H in the manner hereinabove described. The power frame G continues the remainder of its forward stroke without affecting the A frame or pivoted table B. As the return stroke begins the rock arm B2 is started on its return movement since the H frame is carried by drive rods G1, the roller H20 being engaged in recess G24 and roller B3 being moved along the arcuate portion B8 of rock arm B6. During this initial return stroke movement of approximately four and one-half inches, the pivoted table B is swung to the angle shown, and the bottles at the left end of the table B are dropped downwardly to the right to the position shown in Fig. 12, the bottles being stopped by the resilient strips 117. During this movement, the A frame has been returned to its initial position by the action of spring A17, which rotates rock arm A3 to the left as fast as permitted by link A-1, which is in engagement with stud H8.

By this time a second group of bottles has been placed on the feeding table 126, and as lever arm A25 strikes stop bar 123, the shaft A19 will be rotated back, raising the fingers A26 in readiness to advance the second group of bottles to the pivoted table B during the next cycle of operation. As stated above, the drive rod G1 continues its return stroke without carrying the idling power carriage H because of the actuation of the release mechanism H14 by cam shoe G29 on rock arm G26.

Concurrently with the beginning of the next forward stroke the pivoted table B is rotated to the horizontal position as before, as shown in Fig. 13, and the bottles now at the right end of the feeding table B are in position to be transferred to the conveyor C. During this movement of the table B, the centering rollers B19 and B20, which are separated at the beginning of this movement, as shown in Figs. 8 and 12, are pressed against the bottle necks, as hereinabove explained. The bottles are now centered with respect to the conveyor carriers C46, into which they are transferred by the fingers A32 upon the forward movement of the A frame, during this second portion of the forward movement of the power frame G. When the bottles are inserted in the carriers C46 in the manner just described, the bearing blocks C50 are pushed to the right, carrying with them the reciprocating rods C49, as shown in Figs. 31 and 32, the upper cross member G13 having passed to the right a portion of the length of the rods G15 during the first portion of the forward stroke of the G frame. The frame member G13 has moved to the right along ejector rod G15 approximately five inches before the bottles are started into the carriers C46 when the movement of blocks C50 and rods C49 is started. The movement of the rods C49 because of the engagement of spring clips C62 with knobs G17 will cause the ejector rods G15 likewise to be carried to the right. When the bottles are completely inserted in the carriers and the rods C49 are in their outermost extended positions, the rods G15 will be disconnected from spring clips C62 near the end of the forward stroke, and the frame G13 engages the shoulders of knobs G18, carrying the latter at the extreme end of the forward stroke into engagement with the spring clips 92 at the rear end wall of tank 64, as shown in Fig. 8A. As described hereinabove, the foregoing action of the rods C49 causes the brushes inside of the bottles to be extended to the inside walls in readiness for the brushing action, which will occur when engagement is made with the spindles D. The retraction of the ejector rods G15 from the spring clips C62 is necessary in order to permit the movement of the conveyor.

The bottles on the feeding table 126, as before, are, during the second portion of the advance stroke, transferred to the left end of the pivoted table B, as shown in Fig. 14. The next return stroke is accomplished with the same results with respect to the A frame and feeding table B, as before.

When the power frame G has advanced approximately ten and one-half inches, the H frame is released therefrom by the operation of cam bracket 104 in connection with roller H21, and the actuation at this moment of kick-back lever 107, as explained above, is such as to give the H frame a return movement of about one and one-half inches. This reverse movement is sufficient to remove the fingers A32 a sufficient distance from the conveyor carriers C46 to enable the conveyor to be moved, the first movement of which occurs during the last five inches, approximately, of the forward movement of the power frame G, the cam surface C9 of cam shoe C1 actuating roller C14 on the power cross bars C12. During this movement the conveyor is moved a distance equal to two carrier spaces and during the first five inches, approximately, of the return stroke of power frame G, the carrier will be advanced a distance equivalent to two ad-

ditional carrier pockets by the action of cam surface C10 on cam shoe C8, thus bringing four carriers C46 into line for the unloading of any bottles therein and for the loading of the next group of bottles thereinto. The foregoing operations are repeated until there are bottles appearing in the carriers C46 opposite the spindles D at the lower portion of the tank 64. It will be understood that the tank 64 contains an appropriate washing solution to a level somewhat above the spindles D.

During the last half of the next succeeding return stroke of the G frame, the lower cross member G14 will engage engaging edges C63 of spring clips C62, and as the return stroke is continued the rods C49 will force bearing blocks C50 against the necks of the bottles to the left, ejecting the bottles from the carriers, the bottoms of the bottles being engaged by rotating spindle members D19 and D24, which causes the bottles to be rotated, the spindle spring D27 being compressed during this operation. As the bottles are rotated, the brushing or scraping action both inside and out occurs, the entire inner portions of the bottles being washed as the bottles are removed from the brushes C115, and these brushes effectively washing the neck rings of the bottles during this movement. During the first half of the next succeeding forward stroke of the G frame, the bottles are returned to the carriers by the action of spring D27, the insides being again washed as before, and the ejector rods G19 being disconnected from the clips C62 approximately at the middle of the forward stroke. The conveyor is then progressed as before until the washed bottles have been returned to the top central position of the conveyor in the position in which they were inserted into the carriers. During the last half of the next succeeding return stroke the upper frame member G13 will carry ejector rods G15 into engagement with spring clips C62 and actuate rods C49 and blocks C50 to eject the bottles onto the elevator mechanism E, which is in position to receive them, as shown in Fig. 8. During approximately the last inch of the return stroke of frame G, trip fingers F21, actuated from cross plate F8 and rock arm F-1, will engage and rock trip arm E33, which will raise kick-back plate E28 upwardly, resulting in the bottles being thrown forwardly or away from the conveyor a small amount in readiness for the elevating operation about to take place during the first part of the next forward stroke of the G frame. This forward movement will, as before stated, rotate pivoted feeding table B to the horizontal position and will raise the dumping elevator E to the intermediate position, as specifically described in connection with the elevator mechanism. This initial forward movement of the G frame is synchronized through power link 59, rock arm F-1, and link F3 to rock shafts F6 and F10 and cross plate F8, such that rock shafts F6 and F10 are first rotated ninety degrees, raising fingers F23 to the vertical position, which will cause an upward movement of tip members F22 of trip fingers F21, giving the kick-back plate E28 an additional upward movement, insuring the effective removal of the bottle necks from the front edge portions of the conveyor carriers C46 and the centering surfaces C55 of blocks C50. As the forward movement of the G frame and the F mechanism occurs, the plate F8 will be drawn rearwardly,

thus removing trip fingers F21 from the path of the elevator mechanism. During the last five inches of this forward stroke, the elevator shaft E10 will be elevated by elevator member E4 and carried to the dotted position shown in Fig. 14, the final movement of which will be the tilting of the elevator by the engagement of extension arm E34 with stop member E35 on block member 81, as hereinabove described, causing the bottles to be discharged into the inclined portion F19 of trackways F18 of the discharge mechanism.

While I have illustrated and described the preferred form of construction for carrying my invention into effect, this is capable of variation and modification without departing from the spirit of the invention, I, therefore, do not wish to be limited to the precise details of construction set forth, but desire to avail myself of such variations and modifications as come within the scope of the appended claims.

Having thus described my invention, what I claim as new and desire to secure by Letters Patent is:

- 25 1. In an automatic washing machine for containers having a tank and a washing solution therein and a conveyor having a plurality of horizontal carriers to receive and constantly hold the containers in horizontal positions at all times to convey containers into and out of said solution, means in said conveyor adapted to support said containers for the washing operation, said means including a plurality of laterally extensible horizontal brushes.
- 30 2. In an automatic washing machine for containers having a tank and a washing solution therein and a conveyor to convey containers into and out of said solution, means to mechanically wash the containers while in said solution, and means to transfer the containers from said conveyor, and rotate the containers for washing and brushing while in said solution.
- 35 3. In an automatic washing machine for containers having a tank and a washing solution therein and a conveyor to convey containers into and out of said solution, means to mechanically wash the containers, and means to transfer the containers from said conveyor, and rotate the containers for washing and brushing while in said solution, said washing means including a knife-edged scraper adapted to engage the outer side of said containers.
- 40 4. In an automatic washing machine for containers having a tank and a washing solution therein and a conveyor to convey containers into and out of said solution, means for washing said containers while in said solution, and means to remove said containers from said conveyor for said washing.
- 45 5. In an automatic washing machine for containers having a tank and a washing solution therein and a conveyor to convey containers into and out of said solution, means for washing said containers while in said solution, and means to remove said containers from said conveyor for said washing and to replace same in said conveyor.
- 50 6. In an automatic washing machine for containers having a tank and a washing solution therein and a conveyor to convey containers into and out of said solution, means for washing said containers while in said solution, and means to remove said containers from said conveyor for said washing and to replace same in said conveyor.
- 55 70

veyor, said conveyor having means adapted to wash the containers internally during the said removal from the conveyor and return thereto.

7. A container washing machine comprising a tank and a washing solution therein, automatic means to submerge containers in said solution, means to wash said containers internally and externally in said solution, and means to sterilize the containers after washing, said submerging means adapted to remove said containers from said solution prior to sterilization and to move intermittently, laterally in one direction only.

8. In an automatic washing machine for containers having a tank and a washing solution therein, means to convey the containers into and out of said solution, means to wash said containers internally and externally while in said solution, auxiliary means to scrape external labels and dirt from the containers while in said solution, and means to rotate the containers for said scraping and washing externally.

9. In an automatic washing machine for containers having a tank and a washing solution therein and a conveyor to convey containers into and out of said solution, means for washing said containers internally and externally while in said solution, said means including container pockets in said conveyor, brushes fixedly mounted in said pockets adapted to support and center the containers, and means to rotate said containers for said washing and move the same into and out of the pockets and over and off of the brushes.

10. In an automatic washing machine for containers having a tank and a washing solution therein and a conveyor to convey containers into and out of said solution, means for washing said containers while in said solution, said means including container pockets in said conveyor, brushes and scrapers externally of the pockets and acting on the containers externally, brushes in said pockets adapted to brush the containers internally when moved into and out of the pockets, and means to rotate said containers for said washing externally and internally and scraping.

11. In an automatic washing machine for containers having a tank and a washing solution therein and a conveyor to convey containers into and out of said solution, means for washing said containers while in said solution, said means including container pockets in said conveyor, brushes in said pockets adapted to expand within the containers according to the degree of projection of the containers into the pockets, said containers adapted to be extruded from the pockets, and means to rotate said containers for said washing.

12. In an automatic washing machine for containers having a tank and a washing solution therein and a conveyor to convey containers into and out of said solution, means for washing said containers internally and externally while in said solution, said means including container pockets in said conveyor, brushes in said pockets adapted to support, center, and brush said containers internally and said containers adapted to be extruded from said pockets for said external washing.

13. In an automatic washing machine for containers having a tank and a washing solution therein and a conveyor to convey containers into and out of said solution, means for internally and externally washing said containers while in said solution, said means including container pockets in said conveyor, brushes fixed in said

5 pockets having camming means and adapted to support, center and brush containers of different sizes and means to move the containers over and off of the brushes in telescopic relation and acting on said camming means to enlarge and contract the brushes.

14. In an automatic washing machine for containers having a tank and a washing solution therein and a conveyor to convey containers into and out of said solution, means for washing said containers while in said solution, said means including container pockets in said conveyor, brushes fixed at one end and extending into said pockets adapted to be inserted into said containers and having expandable sections to expand therein whereby to support, center and wash the containers, means movable in the pockets adapted to expand and contract the brush sections and means to rotate said containers for said washing.

15. In an automatic washing machine for containers having a tank and a washing solution therein and a conveyor to convey containers into and out of said solution, means for washing said containers while in said solution, said means including container pockets in said conveyor, brushes in said pockets adapted to support said containers, means to move said containers out of the pockets and rotary means adapted to engage and rotate the containers to effect said washing and to move them into the pockets when the last-named means is inoperative.

16. In an automatic washing machine for containers having a tank and a washing solution therein and a conveyor to convey containers into and out of said solution, means for washing said containers while in said solution, said means including container pockets in said conveyor, brushes in said pockets having relatively movable sections adapted to support said containers and resiliently mounted rotary means adapted to be reciprocated axially to engage and rotate the containers to effect said washing and to release the same for movement into the conveyor.

17. In an automatic washing machine for containers having a tank and a washing solution therein and a conveyor to convey containers into and out of said solution, means for washing said containers while in said solution, said means including container pockets in said conveyor, brushes fixed in said pockets adapted to support said containers and axially retractile rotary plunger means in line with the pockets adapted to engage and rotate the containers to effect said washing and means movable in the pockets over the brushes to engage the containers for moving the latter out of the pockets, said rotary means adapted to return the containers to the pockets when the movable means are retracted to permit the latter and containers to move with the conveyor.

18. A container washing machine comprising a tank and a washing solution therein, means to submerge containers in said solution and remove said containers from said solution, means to simultaneously wash said containers internally and externally while submerged, said internal washing means including sections adapted to expand at varying degrees according to the size of the containers and contract within the containers, and means to positively expand the internal washing means according to the lengths and diameters of the containers and degree of projection of the internal washing means into the containers.

19. A container washing machine comprising a tank having a washing solution therein, means to submerge containers in said solution and to remove said containers from said solution, brushes for acting on said containers externally while submerged and brushes for acting on said containers internally while submerged, internal brush entrance portions engaging the mouths of the containers and movable with the containers said latter brushes having means adapted to engage said entrance portions to expand the brushes when passed into the containers and to contract the same on removal from the containers.
20. In a container washing machine, a tank adapted to contain a washing solution, shiftable means to submerge containers in said solution and to remove said containers in horizontal positions from said solution, carriers for receiving the containers, means for projecting the containers into the carriers and for ejecting the same, brushes comprising sections adapted to enter the containers and means acting on said sections for causing expansion or contraction of said sections in the containers after entrance and during removal for action upon the entire inner surface of the containers while submerged.
21. In a container washing machine, a tank adapted to contain a washing solution, intermittently movable means to submerge containers in said solution and to remove said containers from said solution in horizontal positions, horizontal carriers for receiving the containers, reciprocating means for projecting the containers horizontally into the carriers and for ejecting the same, and brushes comprising sections adapted to enter the containers for expansion or contraction therein at one end after entrance and during removal for action upon the entire inner surface of the containers while submerged, said brushes being fixedly mounted axially at one end of each carrier and designed to support and center the containers irrespective of the size of the containers with reference to the carrier.
22. In a container washing machine, a tank adapted to contain a washing solution, means to submerge containers in said solution and to remove said containers from said solution, carriers constituting part of said latter means for receiving the containers, means for projecting the containers into the carriers and for ejecting the same, brushes comprising sections adapted to enter the containers for expansion or contraction therein after entrance and during removal for action upon the entire inner surface of the containers while submerged, and spring means designed to engage said sections at different points along their lengths to cause the same to be expanded or contracted in entering or passing out of the containers and according to the sizes of the containers, said means being positioned along the sections during the washing operation while submerged.
23. In a machine for washing containers having mouth portions smaller than the bodies thereof and of different lengths and diameters comprising brush holding sections mounted for separation at opposite ends and alternately in alignment at reverse ends to move said brushes into and out of engagement with the interior surfaces of the containers, and means acting upon camming surfaces of the sections to expand and contract the same according to their relative position to the containers and the degree of projection of the sections into the containers dependent upon the sizes of the latter.
24. In an automatic machine for washing containers having mouth portions smaller than the bodies and of different lengths and diameters comprising brushes adapted for contraction by contact at the mouth to permit entrance thereof into the containers and for expansion therein, and means engageable with the brushes adjacent the mouth portions to contract the same for removal from the containers.
25. A container washing machine comprising carriers having open ends, and washing means for engaging containers internally and for supporting and centering the same within said carriers comprising brush carrying members alternately separable at opposite ends thereof, and means engageable with said sections to separate said ends or to move the same into alignment as required.
26. In a machine for washing containers of different sizes, brushes adapted to act internally on the containers, said brushes comprising expansible sections having the opposite ends thereof alternately separable for expansion and contraction and expanded and contracted for entrance into and removal from the containers and means for engaging said sections externally to cause the opposite ends thereof to be alternately expanded and contracted.
27. In a washing machine for containers, brushes for acting internally on said containers, comprising pivoted sections, brush heads at the outer ends of said sections, camming surfaces along the lengths of the inner portions of said sections, the outer ends of the sections being designed to move alternatively into divergent relation and substantially in alignment for entering and passing out of the containers, and means engageable with said cam surfaces to cause said sections to move into divergent relation and into alignment.
28. An automatic washing machine for containers having a tank for the washing solution therein, horizontal means for supporting the containers for rotation while submerged in the solution, means for washing the containers internally while submerged and revolving, means for washing the containers externally while submerged and revolving, and means for supporting the containers and simultaneously scraping the same externally while submerged and revolving.
29. An automatic washing machine for containers having a tank for the washing solution therein, horizontal means for supporting the containers for rotation while submerged in the solution, means for washing the containers internally while submerged and revolving, means for washing the containers externally while submerged and revolving, and means for supporting the containers and simultaneously scraping the same externally while submerged and revolving, said internal washing means having means coacting therewith to expand and contract the same within the containers and adapted to support and center the same during the washing operation.
30. In a machine for washing containers of different sizes, comprising a tank adapted to contain a washing solution, means to feed the containers and to move the same laterally in parallel relation, a single common means to suspend and center the containers of varying sizes by varying degrees of expansion and projection into and within the containers, said last named means serving to submerge the containers in the

washing solution, and means to rotate the containers and to brush the same while submerged.

31. In a machine for washing containers of different sizes, means to suspend and center the containers of varying sizes, and means engageable with the closed ends of the containers to rotate the containers, said suspension and centering means including brushes adapted to support the containers, other brushes acting thereon externally, said rotating means adapted to move the containers longitudinally relative to the brushes while the latter are acting on the containers, both internally and externally, while submerged in a washing solution and means acting against the rotating means to remove the containers from the internal container supporting brushes.

32. In a container washing machine, a tank adapted to contain a washing solution, horizontal means for receiving the containers for intermittent movement into and out of the solution, means for brushing the containers internally and externally while in the solution, reciprocable spindles engageable with the containers for rotating the same and moving the containers into the receiving means and horizontal means for moving the containers out of the receiving means and for releasing the spindles to move the containers into the receiving means.

33. In a container washing machine, a tank adapted to contain a washing solution, means for receiving the containers for movement into and out of the solution, means for brushing the containers internally and externally while in the solution, spindles engageable with the closed ends of the containers for intermittently rotating the same, and movable therewith while the brushes and containers are moved relatively to cause the brushes to operate on the container throughout the length thereof and means movable with the spindles to expand and contract the internal brushes automatically, said

brushes adapted to enter the containers in a contracted condition and to expand while entering and to contract in being removed therefrom.

5 34. A container washing machine comprising a tank adapted to contain a washing solution, means for conveying the containers into and out of the solution, said containers being movable longitudinally into and out of the conveying means, stationary brushing means carried by the conveying means, said containers being movable longitudinally relative to the brushing means, and means for rotating the containers during the brushing action and movable therewith during the movements aforesaid.

10 35. In a container washing machine, means for receiving the containers in horizontal positions endwise while supported on the sides, means for moving the containers into upper and lower tiers, means for feeding unwashed containers and discharging washed containers in an upper tier, and brushing means adapted to expand and contract to conform to the contour of the containers and relative to which the same are movable during the brushing operation, said containers being washed in a lower tier.

20 36. In a container washing machine, means for receiving the containers in horizontal positions endwise while supported on the sides, means for advancing the containers into upper and lower tiers, means for feeding unwashed containers and discharging washed containers in an upper tier, brushing means adapted to conform to the contour of the containers and relative to which the same are movable during the brushing operation, and means engageable with the containers to rotate the same while being brushed, said means being disengaged during the feeding movements of the containers and during the advancement of the containers into upper and lower tiers.
